WIND MUSICAL INSTRUMENT

Willard P. Dausman, Elkhart, Ind., assignor to
C. G. Conn, Ltd., Elkhart, Ind., a corporation
of Indiana

Application June 29, 1932. Serial No. 619,851

6 Claims. (Cl. 84—392)

My invention relates to the piston valves of cornets, and similar musical instruments, and more particularly to the valve keys for such instruments.

5 The piston valves of cornets, and other musical instruments which are provided with reciprocating valves, are provided with some means to prevent casual rotation of the valve within its casing in order that the proper registration of the 10 valve ports and passages with the valve casing ports and passages may be maintained. Such a means to prevent valve rotation has taken many and various forms, all of which are more or less effective, and all of which are objectionable to 15 some degree, especially because of excessive friction and wear.

The principal object of my invention is to provide improved and simplified means to prevent casual rotation of the piston valve of a cornet, 20 and like instruments, this improved means comprising a stationary rod-like key which has a sliding telescopic connection with the piston valve, and which is disjoined from the valve casing.

25 Another and more specific object of my invention is to provide a valve key which has a telescopic sliding connection with the piston valve and which is disposed between the valve stem and the valve casing.

30 Other and more specific objects of the invention are mentioned and described herein.

The preferred embodiment of my invention is illustrated in the accompanying drawing, wherein:

35 Figure 1 illustrates a fragmental side view of a wind musical instrument of the cornet type and including the three piston valve casings, and associated parts;

Fig. 2 is an enlarged sectional view, partially in section, of one of the cornet valve casings, its piston valve, and other details and parts, illustrating the application of my invention thereto with the valve in the elevated position;

45 Fig. 3 is a similar view in fragmental section illustrating the piston valve in the depressed position;

Fig. 4 illustrates two side elevational views of the valve key and the head plate therefor;

50 Fig. 5 illustrates a bottom plan view of the valve key head and valve key connected therewith; and

Fig. 6 illustrates a modified form of the valve key head.

55 Similar numerals of reference indicate like

parts throughout the several views on the drawing.

Referring now to the details of the drawing the numeral 1 indicates a tubular cornet valve casing of the conventional type and within which the usual reciprocating cylindrical piston valve 2 is arranged, said valve being normally upwardly urged by a coil spring 3 which is disposed within the casing 1 and seated upon the inner face of the casing bottom cap 4. The valve 2 may be provided with the usual ports and passages—not shown—which are well known in the art, and may be provided also with the top head member 5 which is rigidly mounted in the upper end of the tubular cylindrical portion thereof. For reciprocally depressing the valve 2 a stem 6 is rigidly and centrally connected therewith in the head portion at 7, said stem extending upwardly through the aperture 8 provided in the casing top head 9 which may be screw threaded upon the valve casing 10, as is well known.

The finger tip 11 may be mounted upon the upper end of the stem 6 exteriorly of the casing cap 9 for actuating the valve 2. The numeral 12 indicates a flat substantially circular plate or disk which functions as the head for the rod-like key 13, the latter being rigidly fastened in the former at 14 at a point intermediate the center of said disk and its outer periphery and extending at substantially right angles thereto. The disk 12 may be provided with the relatively thin marginal flange 15 and a radially arranged stop lug 16, the latter being preferably coextensive with the outer periphery of the marginal flange 15 of said disk.

The disk 12 is adapted to be clamped between the upper end of the valve casing 1 and the casing cap 9, and when so fastened the flange 15 rests against the end of the valve casing and the reduced body portion of said disk fits within the bore of the valve casing with slight clearance and with the stop lug 16 engaging in a slot 17 formed in the edge of the valve casing 1. In the position of the disk 12, as above described, the casing cap 9 is screwed snugly against the upper surface of the disk 12, the engagement of stop lug 16 in casing slot 17 confining the disk 12 against rotational displacement.

The disk 12 is provided with a central aperture 18 which is traversed by the stem 6, with slight clearance to eliminate friction between the parts. The rod-like key 13 depends from the disk or head 12 substantially parallel with the axis of the stem 6 and engages slidably in a bearing hole 19 formed in the valve head 5, in which hole said key 110

fits with very slight clearance, said hole extending substantially parallel with the axis of the valve 2.

From the foregoing it will be evident that the engagement of the disk lug 16 in the slot 17 effectually prevents casual rotation of the disk 12, and that the rod-like key 13, which depends from said disk and which slidably engages the bearing hole 19 in the valve head 5, effectually confines the valve 2 against casual rotation. The refined form of the key 13 contemplates a highly polished cylindrical member which slidably engages the bearing hole 19 with so little friction that the engagement is practically without wear on either of the parts.

15 In the modification illustrated in Fig. 6 the key head 12 is lengthened substantially and provided with a tapered lower end 20 to facilitate its introduction to the casing interior. And in this structure a yieldable ring-like disk 21, made of cork or other suitable yieldable material, is mounted in a suitable recess provided in the upper face of the member 12, said disk 21 preferably projecting above the plane of the flange 15 of said head and being directly engaged by the 25 cap 9 when the latter is screwed into position on the casing 1.

I claim:

1. In a wind musical instrument of the character described, the combination with the valve 30 casing, the reciprocatory valve therein, and a valve casing cap, of means to prevent casual rotation of said valve, said means comprising an anchorage element mounted between said valve casing end and said casing cap, means to prevent rotation of said anchorage element, and an elongated key rigidly connected with said anchorage element and extending downward into the valve casing bore into slidable telescopic relation with said valve.

40 2. In a wind musical instrument of the character described, the combination with the valve casing, the reciprocatory valve therein, a stem for said valve, and cap for said valve casing, of means to prevent casual rotation of said valve, 45 said means comprising an apertured anchorage element mounted between said valve casing end and said casing cap, and an elongated key rigidly connected with said anchorage element and extending downward into the valve casing bore into telescopic slidable relation with said valve, said valve stem traversing the aperture in said anchorage element.

3. In a wind musical instrument of the character described, the combination with the valve 55

casing and a reciprocatory valve therein, of means to prevent rotation of said valve, said means comprising an element rigidly mounted adjacent the end of said valve casing, a yieldable element mounted thereon, an elongated key within said valve casing and disjoined therefrom, and a slideable telescopic connection for said key between said rigidly mounted element and said valve.

4. In a wind-musical instrument of the character described, the combination with the valve 80 casing, the reciprocatory valve therein, and a valve casing cap screw threaded to said casing, of means to prevent casual rotation of said valve, said means comprising an anchorage element mounted between said valve casing end and said casing cap and provided with a yieldable pad which is engaged by said casing cap, means to prevent rotation of said anchorage element, and an elongated key rigidly connected with said anchorage element and extending downward into the valve casing bore into slideable telescopic relation with said valve.

5. In a wind musical instrument of the character described, the combination with a valve 85 casing, a reciprocatory valve therein, an apertured removable cap for said valve casing, and the valve stem for said valve, of means to prevent rotation of said valve, said means comprising a centrally apertured element nonrotatably mounted between said valve casing and the cap therefor, said valve stem traversing said aperture of said element, and an elongated key connected with and depending from said centrally apertured element and projecting downward into the valve casing bore eccentrically thereof into slideable telescopic 95 relation with said valve.

6. In a wind musical instrument of the character described, the combination with a valve 100 casing, a reciprocatory valve therein, a centrally apertured casing cap removably mounted on said 105 casing, and a valve stem connected with said valve and traversing said casing cap aperture, of means to prevent rotation of said valve when reciprocally actuated, said means comprising a centrally apertured anchorage plate nonrotatably mounted between said valve casing and the cap therefor, said valve stem traversing said anchorage plate aperture, and an elongated key connected with and depending from said anchorage plate and projecting downward into the valve casing 110 bore eccentrically thereof and into slideable telescopic relation with said valve.

WILLARD P. DAUSMAN.
